ASH TRAY

George Goodwin, New York, N. Y.

Application August 20, 1949, Serial No. 4,627

Term of patent 14 years

(Cl. D85—8)

To all whom it may concern:

Be it known that I, George Goodwin, a citizen of the United States of America, residing in New York city, county of New York, and State of New York, have invented a new, original, and ornamental Design for a Combined Tobacco Can Cover, Pipe Rest, Match Book Holder, and Ash Tray, of which the following is a specification, reference being had to the accompanying drawing, forming part thereof, wherein,

I claim:

The ornamental design for a combined tobacco can cover, pipe rest, match book holder, and ash tray, substantially as shown.

GEORGE GOODWIN.
